CLAIM

We claim the ornamental design for a charging pocket, as shown and described.

DESCRIPTION

FIG. 1 is a perspective view of the charging pocket on a backpack in which the charging pocket contains a mobile device;

FIG. 2 is a perspective view of the charging pocket of FIG. 1 without a mobile device;

FIG. 3 is a front view of FIG. 1;

FIG. 4 is a back view of FIG. 1;

FIG. 5 is a side view of FIG. 1;

FIG. 6 is another side view of showing the side opposite that shown in FIG. 5;

FIG. 7 is a top view of FIG. 1;

FIG. 8 is a bottom view of FIG. 1;

FIG. 9 is a partial sectional view taken along line 9-9 of FIG. 3 showing an interior panel of the charging pocket with a charging status window; and,

FIG. 10 depicts the interior of the backpack with a pocket containing a charging device for charging a mobile device inductively or with a charging cable through the grommetted port.

The broken lines represent unclaimed environmental subject matter and stitching on and around the charging pocket. The dot-dash lines illustrate the boundaries of the claimed portions as well as unclaimed portions of the charging pocket.
